ABSTRACT

A method for manufacturing table tennis balls. The halves of a ball are formed in a single sheet and the sheet is separated to separate the formed halves of the ball. One of the portions of the sheet containing a ball half is inverted relative to the other and the portions are aligned so as to align the ball halves the rein. The sheet portions are then welded together to join the ball halves and the completed ball is removed from the joined sheet portions.

METHOD FOR THE MANUFACTURE OF HOLLOW PLASTIC ARTICLES

This invention relates to methods for the manufacture of hollow plastic articles particularly table tennis balls and is a continuation in part of our U.S. patent applications Nos. 601,591 and 601,592, both now abandoned.

Table tennis balls of the best quality are a precision product which must meet strict standards of weight and diameter and must be as nearly perfectly spherical as possible.

In the past table tennis balls have generally been made from cellulose nitrate by a method which involved forming ball halves from sheets of that material and attaching the ball halves together by treating the edges of the halves with solution one half being provided with a lip which fits inside the other half.

The fitting together of the halves is carried out largely by hand and the method suffers from the disadvantages that the cellulose nitrate and solvent used are highly inflammable and the accuracy of the method is poor so that a high proportion of low standard balls is produced, the balls having to be carefully graded.

Other types of ball which do not need to be made to a precise standard, e.g., hollow rubber balls, have been made by pressing ball halves in sheets of rubber and folding the sheets of rubber to bring the halves together.

This method cannot be applied, however, to the manufacture of table tennis balls since the stiff plastics materials needed to be used cannot be folded satisfactorily to give the required precision.

It has been proposed to make other low precision products, e.g., Christmas tree balls, by forming halves of the article in separate sheets of material and placing together the separate sheets to unite the halves of the article. This method produces inferior table tennis balls, however, since small differences in the thickness of the separate plastic sheets used cause the balls to be unbalanced.

According to the invention a method of manufacturing table tennis balls comprises forming the two halves of a table tennis ball in a sheet of thermoplastic material, dividing the sheet into two separate parts each of which contains one half of said table tennis ball, inverting one part of the sheet relative to the other part of the sheet by means of movable sheet gripping means and locating said two parts adjacent one another in a superposed relationship so that the two halves of said table tennis ball are aligned in substantially the relative positions they occupy in the finished table tennis ball, joining said two parts together to form the table tennis ball and removing the table tennis ball from the sheet.

According to the invention also apparatus for use in the manufacture of hollow plastics articles comprises parting means for dividing the sheet into two separate parts each containing one half of the article, supporting means for the parts of the sheet, means for gripping one part of the sheet, means for producing relative movement between said one part of the sheet and its supporting means to move said one part of the sheet out of contact with its supporting means, means for inverting said one part of the sheet while it is out of contact with its supporting means, and means for locating the two parts together on the supporting means so that the halves of the article are in substantially the relative positions they occupy in the finished article.

Preferably the supporting means for the parts of the sheet is formed in two sections, one for each of the parts of the sheet, and the two sections are relatively movable to enable one part of the sheet to be moved out of contact with its supporting means to permit that part of the sheet to be inverted.

The method of this invention enables table tennis balls to be made to very high standards of precision economically and with a lower proportion of sub-standard balls than has previously been achieved.

The invention will now be described, by the way of example only with reference to the accompanying drawings in which:

FIGS. 1A, 1B, 1C together are a plan view of an apparatus for carrying out the method of invention.

FIG. 2 is a partial view of the apparatus in the direction of Arrow A of FIG. 1.

FIG. 3 is a partial view of the apparatus in the direction of Arrow B of FIG. 1.

FIGS. 4A, 4B together are a partial view in cross-section of the apparatus taken along the line C—C of FIG. 1.

FIG. 5 is partial front elevation, partly in section, of the apparatus taken along the line D—D of FIG. 1.

FIG. 6 is a view partly shown looking in the direction of Arrow E of FIG. 5.

FIG. 7 is a cross-sectional view of the apparatus shown in FIG. 1 and looking in the direction of Arrow F of FIG. 1.

FIG. 8 is a partial view, partly broken away and sectional, taken in the direction of Arrow G of FIG. 7.

FIGS. 9A, 9B together are a partial view in cross-section, taken along the line H—H of FIG. 1.

FIG. 10 is a partial front view of the apparatus of FIG. 9 in the direction of Arrow K of FIG. 9.

FIGS. 11A, 11B and 11C together are views, partly in cross-section, of the apparatus, viewed along the line L—L of FIG. 1 and

FIGS. 12A, 12B together are a view on Arrow M of FIG. 11B.

A table-tennis ball making machine is mounted on a rigid floor mounted frame 1 which has an invented T-shape cross-section. Located on the front face 2 of the vertical leg 3 of the frame are eight stations at equidistant centers. In each station is apparatus for performing one or more operations required during the manufacture of a table-tennis ball from a sheet of thermoplastic material. The stations are definitively titled feed station 100, heating station 200, forming station 300, cutting and doubling station 400, welding station 500, idle station 600, cropping and trimming station 700, and discharge station 800. Transferring means are provided for moving a sheet of material from one station to the next. Rotatably mounted on the base 4 of the frame at the rear of the central leg 3 is a camshaft 5 which extends the length of the frame. A plurality of cams is mounted on the camshaft and these are connected by cam followers to the apparatus and the transferring means to control the sequence of operations of the machine during manufacture. The camshaft is connected to a reduction gearbox 6 which is driven by a constant speed electric motor 7 so that the camshaft 5 rotates at a constant angular velocity.

The transferring means and the apparatus located in each station will now be described in more detail.

Transferring Means

Two reciprocable rectangular-cross-section gripper-carrying bars 10 extend longitudinally of the frame 1 over substantially the full length of the frame. The bars are mounted in parallel relationship in bearings forming part of brackets extending horizontally from the vertical leg of the frame so that the bars are reciprocable longitudinally in a horizontal plane. The left-hand end of each bar as seen in FIG. 1 is attached to one of the ends of lever arms 11. The other ends of the lever arms are keyed to a shaft 12 which is oscillated by a system of gears 13 rotated by cam 13a through shaft 13b and actuated by a lever system connected to a cam follower 14 which follows the contour of a gripper carrying bar actuating cam 14a. Rotation of this cam causes shaft 12 to oscillate periodically through a predetermined angle which cause the gripper carrying bars 10 to reciprocate. The angle is such the bars reciprocate over a distance equal to the center distances between the stations.

Attached equidistantly along each gripper-carrying bar 10 are seven U-shaped gripper carrying members 15. The members 15 are spaced apart along the shaft at distances equal to the center distances of the stations. Each of the members on one bar has an opposite correspondingly placed member on the other bar. Each member carries a sheet gripper 16 comprising a pair of sheet clamping members 17 (see FIG. 2) horizontally rotatably mounted one above the other in the legs of the U-shaped carrying member 15. A pair of inter-engaging pinions 18, one secured to each clamping member, ensures equal angular movement of the clamping members.

An extension 19 of each lower clamping member 17 is engageable by an opening arm 20 attached to a rotatably mounted gripper opening shaft 21 extending longitudinally of the frame below the gripper carrying bars. Each shaft 21 is connected by levers 22 to a cam follower 23 which follows a gripper opening cam 24 on the camshaft 5.

In general, upon rotation of the gripper-carrying-bar actuating cam 14a and the gripper opening cam 24, each pair of grippers 16 clamps on to a sheet located in a station, moves to the right (see FIG. 1) to transfer the sheet to a succeeding station, opens to release the sheet, and returns to the first-mentioned station. However, in some stations, the grippers perform additional functions as will be seen.

Feed station (100)

A U-shaped bracket 101 (FIG. 2) is bolted by one leg 102 of the U to the vertical leg 3 of the frame and extends in cantilever fashion from the frame. Apertures are formed in each leg of the U for the passage therethrough of the gripper carrying bars 10 and the gripper opening shafts 21 and bearings 103 are mounted on the bracket for carrying the bars and shafts.

Mounted on the upper ends of the legs of the bracket is a feed hopper 104. The hopper comprises a rectangular bottom frame 105 which is bolted to the tops of the legs of the U-shaped bracket and extends in cantilever fashion parallel to the main frame. Attached to each inner corner of the frame is an L-shaped column 106. The four columns extend upwardly and their inwardly facing surfaces 107 (FIG. 1) define the hopper. Sheets of material to be used in the machine are of a size such

that when placed horizontally in the hopper they are almost in contact with the inwardly facing surfaces 107 of the columns 106. Bolted to the undersurface of the frame are sheet separators 108 which extend inwardly of the columns to support on their upper surfaces 109 a stack of sheets in the hopper. Each separator has two teeth 110 below the sheet carrying surface 109 which face inwardly of the hopper.

10 A suction pad carrying frame 111 is slidably mounted on the bracket 101 below the hopper 104 and is adapted to slide towards and away from the hopper as an operating rod 112 connected to the base of the carrying frame follows through lever 113a a suction pad carrying frame actuating cam 113 on the camshaft 5.

15 Two suction pads 114 are mounted on the upper side of the frame with the engaging surfaces of the pads facing the lowermost sheet in the hopper. A source of 20 vacuum is connected through passages 115 to the engaging surfaces.

25 In operation when the hopper 104 carries a stack of sheets the frame 111 is moved upwards until the engaging surfaces of the suction pads 114 contact the undersurface of the bottom sheet in the stack. Vacuum is applied to the pads and the frame is lowered away from the hopper. This causes the sheet to be bent and pulled over the sheet separators 108. If the sheet immediately 30 above the bottom sheet sticks to the bottom sheet, the teeth 110 of the separators 108 break the adhesion and ensure that only one sheet at a time is removed from the hopper.

35 The suction pad carrying frame 111 is lowered until the sheet is in line with the line of motion of the grippers 16 and then stopped from further movement by a well on the cam 113 while the first pair of grippers is moved from the heating station and closed on the edges of the sheet as shown chain dotted outline in FIG. 2. 40 The vacuum source is cut off to release the sheet from the suction pads. The frame 111 is then lowered further clear of the sheet and the gripper carrying bars 10 operated to transfer the sheet to the next station, the heating station.

45 Heating station (200).

50 Upper and lower dovetail slideways respectively 201 and 202 (FIG. 3) are attached to the central leg 3 of the main frame and above and below the gripper carrying bars 10. In the slideways 201 and 202 are movable slides respectively securely attached to an upper right-angle swan neck bracket 203 and a lower right-angle swan neck bracket 204. On the end of each bracket remote from the slides is mounted a heating box. The 55 lower heating box 205 is rigidly mounted with respect to the lower bracket 204 but four compression springs 206 are located between the upper heating box 207 and the upper bracket 203, the heating box being movable towards the end of the bracket against the pressure of the springs.

60 Each heating box has an open end 208 and the open ends of the boxes face each other across the line of movement of sheets of material. The ends of the boxes opposite the open ends and adjacent the ends of the swan-neck brackets are formed by electrical heating elements 209 in the form of expanded metal heaters extending over the whole area of that end of the box.

The upper bracket 203 and lower bracket 204 are connected respectively by connecting rods 210 and 211 and a lever mechanism 212 to the followers 213 and 214 of heater bracket actuating cams 215 and 216 on the camshaft 5.

In operation, the heaters 209 are energized and the first pair of grippers 16 brings a sheet of material from the feed station 100 to the heating station 200 and stop when the sheet is between the heating boxes 205 and 207, which are spaced-apart (in the position shown in FIG. 3). Continued rotation of the camshaft 5 and the heater bracket actuating cams 215 and 216 causes the brackets to slide in the slideways 201 and 202 towards each other to clamp the sheet between them, the compression springs 206 ensuring even clamping about the periphery of the sheet. The sheet is heated while the first pair of grippers is opened and returns to the feed station and the second pair of grippers returns from the forming station 300 and close onto the sheet. When the sheet has been heated to the required temperature the heater boxes are moved away from each other. The second pair of grippers then transfers the heated sheet to the forming station.

Apparatus for heating sheets of thermoplastic material similar to that described above is disclosed in the specification of our U.S. Pat. No. 3,196,488.

Forming Station (300)

The apparatus in the forming station is of the kind described in the specification of our U.K. Pat. No. 1,131,361.

Slidably mounted on the central leg 3 of the main frame are an upper right-angle swan neck bracket 301 (FIG. 4) and a lower right-angle swan neck bracket 302. The slides 303 and 304 comprise a plurality of recirculatory roller bearings 305 which substantially prevent any unwanted relative movement between the brackets 301 and 302 and the frame. The upper and lower brackets are movable towards and away from each other by means respectively of cam followers 306 and 307 which follow actuating cams 308 and 309.

The upward facing end 310 of the lower bracket 302, remote from the frame carries a male mold assembly 311. The male mold assembly comprises a supporting plate 312 bolted to the end of the bracket and a mold carrying member 313 secured to the plate. The plate is provided with electrical heating elements (not shown) for heating the plate and the mold carrying member.

The mold carrying member 313 is a metal block with sixteen bores 314 accurately machined therein and opening onto the upper surface of the member. In each of the bores is located and secured a male mold 315. Each mold has a locating portion which extends into the bore and a molding portion with a surface 316 which is in the form of a minor segment of a sphere. The molding portion has a height of approximately one quarter of the diameter of the sphere. Passageways 317 for connection to either a source of vacuum or atmosphere extend from the molding surface of the assembly.

An open-ended lower clamping box 318 surrounds the male mold assembly and is secured to a hollow rectangular base plate 319 surrounding the end of the bracket below the mold assembly. Two opposite sides of the base plate are mounted on plungers 320 movable in bearings 321 mounted on the bracket 302 connected

by pin 324 to a cam follower 322 which follows a clamping box actuating cam 323 in a similar manner to that described below for an upper clamping box.

The upper bracket 301 carries a female mold assembly 325 on the downward facing surface of the end 326 thereof remote from the frame. The female mold assembly comprises a mounting plate 327 bolted to the upper bracket and a female mold carrying member 328 secured to the mounting plate. The mounting plate has passageways 329 therein for cooling fluid.

The female mold carrying member has sixteen bores 330 accurately machined therein which extend upwardly from the downward facing surface of the member 328 for the reception of 16 female molds 331 having molding surfaces 332 in the form of a hemisphere. The female molds 331 and the male molds 315 carried on the lower bracket are directly in line. Passageways 333 connectable to either a source of vacuum, atmosphere, or to a source of pressurized gas extend from the molding surface of the female molds.

An upper open-ended clamping box 334 surrounds the female mold carrying member 328 and is resiliently mounted on an upper base plate 335 surrounding the end 326 of the upper bracket 301. The box 334 is resiliently urged away from the base plate 335 by springs 336. The base plate is mounted on the upper bracket by plungers 337 running in bearings 338 and connected by pins 339 and levers 340 to an actuating cam follower 341 and cam 342 in the same manner as the lower base plate is moved on the lower bracket.

In operation of the forming station a heated and softened sheet of material is brought by the second pair of grippers into the forming station. The appropriate cam followers 322 and 341 are actuated to move the clamping boxes 318 and 334 towards each other and relative to their respective brackets 302 and 301 into clamping engagement with the periphery of the sheet, the spring loading of the upper box 334 ensuring even clamping of the sheet. The grippers are caused to release the sheet and return to the heating station.

The lower bracket cam follower 307 is then operated to move the male mold assembly 311 towards the sheet until the upper surface of the mold carrying member 313 is level with the sheet clamping upper surface of the lower box 318. The passageways 317 extending through the male molds 315 are connected to the vacuum source to draw the sheet over the molds to form 16 domes in the sheet. Since the male molds are heated the sheet does not cool appreciably.

Next the upper bracket cam follower 306 is operated to lower the female mold carrying member 328 into clamping engagement with the sheet so that the domes extend into the cavities in the female molds 331. The vacuum source is shut off from the male molds and applied through the passageways 333 in the female molds to draw the sheet up into contact with the molding surfaces 332 of the female molds 331 to form 16 hemispheres in the sheet. Since the female mold assembly 325 is cooled by a cooling fluid passing through passageway 329 the sheet hardens on contact with the molds.

The vacuum source is shut off from the female molds and pressurized air supplied through passageways 333 to break adhesion between the sheet and the molding surfaces. The third pair of grippers 16 is clamped onto

the trailing half only of the sheet of material for a reason which will be seen shortly and after the upper and lower clamping boxes and brackets are moved away from each other, the third pair of grippers transfers the sheet to the next station.

Cutting and Doubling station (400)

In this station the sheet is cut into two parts, transversely of the line of motion of the sheet, each part having eight hemispheres, the leading part is rotated through 180° by rotation of the fourth pair of grippers and the trailing part of the sheet is pushed over the leading part to form a double thickness of sheet having eight spheres therein.

A right-angle swan neck bracket 401 (FIGS. 5 and 6) is slidably mounted in a dovetail slide 402 on the central leg 3 of the main frame 1 above the line of motion of the sheet. The bracket is connected in the usual manner by means of a connecting lever mechanism 403 to the cam follower 403a of an actuating cam 403b. Bolted to the end 404 of the bracket remote from the slideway is a mounting plate 405 which may be considered as having two sections, a trailing section 405a and a leading section 405b, i.e., a trailing section under which the trailing half of the sheet comes to rest and a leading section under which the leading half of the sheet comes to rest.

Mounted in the trailing half 405a of the plate 405 are spring-loaded clamping plungers 406 having at their ends cup shaped clamping pads 407. The plungers 406 are positioned in the mounting plate 405 so as to be approximately over the hemispheres in opposite corners of the trailing half of the sheet. The clamping pads are urged away from the plate by the springs 408.

Parting means for dividing the sheet into two parts comprises a knife blade 409 extending transversely of the sheet which is secured to the mounting plate between the leading and trailing sections thereof in a position above the predetermined parting line of the sheet located in the station.

The means for moving the trailing part of the sheet over the leading part form a part of the upper bracket 401. The mounting plate 405 has a dovetail slideway 410 formed therein extending longitudinally of the plate. A slide 411 is located in the slideway and attached to a pin 412 which moves in a slot 413 in the end 404 of the bracket. A collar 414 attached to the end of the pin remote from the slide is slidable on the end of a lever 415 pivoted to the bracket and swingable about the pivot 416 by a lever mechanism 415a operating on the end 417 of the lever remote from the collar which is controlled by a cam follower 415b actuated by a cam 415c on the camshaft 5. Movement of the lever 415 causes the slide 411 to move one way and the other along the dovetail slideway. Attached to the extreme trailing end of the slide is a pusher member 418 adapted to engage the last line of hemispheres in the sheet.

Also secured to the dovetail slide is a bar 419 extending transversely of the plate. The ends 420 of the bar form cams for opening the grippers on movement of the slide 411 as will be described.

A generally rectangular lower bracket 421 is bolted to the central leg of the main frame and extends cantilever fashion below the upper bracket 401.

Mounted on the upper surface of the lower bracket is a supporting plate 422 for the trailing part of the sheet. The plate is mounted on four plungers 423 with compression springs 424 between the plate and the bracket to urge the plate away from the bracket to the extent allowed by the plungers. The springs 424 are stronger than the springs 408 provided for the clamping plungers 406.

A supporting plate 425 for the leading part of the sheet is mounted on a supporting bracket 426 vertically slidably mounted in a dovetail slide 427 secured to the forward facing side of the lower bracket 421. The supporting plate has eight bores 428 formed therein for the reception of hemispheres as will be described. The rearward edge of the plate has a hardened metal strip 429 secured thereto to provide a bolster for the cutting knife 409 and the forward edge of the plate has a stop 430 attached thereto. An actuating cam 450, cam follower 451, and lever system 452 connected to an actuating link 431 are provided for moving the supporting bracket 426 in the slideway 427.

The fourth pair of grippers is of different construction to that described earlier and will now be described in detail.

Each gripper comprises a pair of sheet clamping members 436 (FIG. 7) rotatably mounted in a U-shaped carrying member 440 as described previously. Interengaging pinions 438 are also provided on each clamping member. However an extension 439 is provided on each clamping member 436 for engagement by a gripper opening mechanism, the mechanism comprising either the gripper opening shaft 21 or the gripper opening cams 420 provided on the dovetail slide 411 on the upper bracket 401 of the cutting and doubling station.

The carrying member is mounted on the end of a shaft 440 which extends through and is rotatably mounted in circular aperture in the gripper carrying bar 10. The other end of the shaft has a tongue 441 of rectangular cross-section.

Two holes 442 (FIG. 8) are provided in the carrying bar at opposite ends of an extension of a diameter of the aperture in the bar, i.e., 180° apart with respect to the center of the aperture. A spring-loaded ball 443 is mounted in the carrying member and is engageable with either of the holes 442 in the carrying bar to locate it in one or other of two positions which are 180° displaced.

Two means for rotating the grippers are mounted one on the central leg 3 of the main frame and one on the free end of the cantilever lower bracket 421. Each means comprises a driven shaft 444 rotatably mounted and extending transversely with respect to the gripper carrying bar 10. One end 445 of the driven shaft is provided with a slot therein which is engageable by the tongue 441 of the shaft 440 carrying the carrying member. The other end of the driven shaft carries a sprocket 446. Below the driven shaft 444 is a driving shaft 447 which carries a second sprocket 448 and a driving chain 449 engages both sprockets. The driving shaft 447 is oscillated intermittently by means of a linkage system actuated by a cam 453 and cam follower 454 (see FIG. 1) through 90° to rotate the driven shaft through 180°.

In operation the third pair of grippers 16 brings a sheet of material with 16 hemispheres formed therein from the forming station. The grippers clamp on the trailing half of the sheet only. The grippers stop when the leading and trailing halves of the sheet are resting on or located above their respective supporting plates 425 and 422 and the leading edge is adjacent the stop 430 provided on the leading supporting plate 425. The third pair of grippers then return to the forming station and the fourth pair of grippers enter the cutting and doubling station and the clamping members 436 thereof close on the leading half of the sheet and in this position the tongue 441 of the carrying member shaft 440 is in engagement with the slot in the end 445 of the driven shaft 444.

The upper bracket 401 is lowered so that the cup shaped clamping pads 407 engage hemispheres at opposite corners of the trailing half of the sheet, to clamp the trailing half of the sheet to its supporting plate 422. Still further downward movement brings the knife 409 into contact with the sheet and severs the sheet in two halves each containing eight hemispheres the springs 424 under the trailing half supporting plate allowing the plate and the trailing half of the sheet to lower under cutting pressure of the knife.

When the sheet has been severed the upper bracket 401 is retracted withdrawing the knife 409 and the clamping pads 407. The appropriate cam 450 on the camshaft 5 then actuates the lever system 452 to lower the leading half supporting bracket 426 and plate 425 away from and clear of the leading half of the sheet.

The gripper rotating means are actuated to rotate the grippers through 180°, the spring-loaded balls 443 35 locating in the holes 442 provided in the gripper carrying bars 10 to ensure that the angle of rotation is exactly 180°. The hemispheres in the leading half of the sheet now have their open sides facing upwards.

The leading half supporting plate 425 is now raised until its upper surface is slightly below the upper surface of the trailing half supporting plate 422. The slide member 411 provided on the upper bracket is then operated by the lever 415, collar 414, pin 412 from lever system 415a and cam 415c firstly to bring the gripper opening cams 420 into engagement with the upwardly extending extensions 439 of the grippers to open the grippers and allow the leading half of the sheet to fall onto its supporting plate 425, the hemispheres becoming located one in each bore 428 provided in the supporting plate, and then for the pusher member 418 to engage the last line of hemispheres on the trailing half of the sheet and push the trailing half off the supporting plate 422 and against the stop 430 provided on the leading half supporting plate 425, and to rest on the leading half of the sheet with the hemispheres on each half substantially in line to form eight spheres as shown in chain dotted lines in FIG. 5.

On retraction of the slide member 411 the fourth pair of grippers clamp again onto the double thickness of sheet, the leading half supporting member 426 is lowered, and the sheet transferred to the next station.

Welding Station (500)

Apparatus for forming hollow plastic articles by High Frequency welding is described in the specification of our U.S. Pat. No. 3,411,974.

More particularly the apparatus comprises an upper right-angle swan neck bracket 501 (FIG. 9) and a lower right-angle swan neck bracket 502 slidably mounted on the central leg 3 of the frame in recirculating roller bearings 504 in a similar manner to the brackets 301 and 302 of the forming station 300 of the apparatus described in this specification.

Secured to the lower end 505 of the upper bracket, i.e., that end remote from the frame, is an upper electrode mounting assembly 506 which comprises a temperature control plate 507 secured to the bracket, a spacer plate 508 secured to the control plate, and an electrode holding plate 509 secured to the spacer plate. The temperature control plate has a bore 510 formed therein for the passage of heating or cooling fluid to maintain the temperature of the electrode holding plate substantially constant. The electrode holding plate 509 has eight circular bores extending therethrough in each of which is located a cylindrical electrode 511. The lower face 512 of each electrode is hemispherically recessed, the sphere of which it forms a part having a diameter equal to the diameter of the finished table-tennis ball.

25 The spacer plate 508 has a recess 513 formed in its lower surface so that when the plates are assembled a chamber is formed between the spacer and holding plates. A passageway 514 is formed through the bracket, and control and spacer plates, for connecting the chamber so formed to a source of vacuum. Further passageways 515 through each of the electrodes connect the chamber with the hemispherical surfaces of the electrodes.

30 A lower electrode mounting assembly 516, of identical construction to the upper electrode mounting assembly described above, is mounted on the end 517 of the lower bracket 502 by means of six ceramic spacer rods 518 so that the hemispherical surfaces 519 of the lower electrodes are directly opposed to the hemispherical surfaces 512 of the upper electrodes 511.

A High Frequency electrical energy source (not shown) is mounted on the frame adjacent the upper assembly 506. A coaxial cable 521 (FIG. 10) from the High Frequency source has a first conductor 522 connected between the temperature control plate 507 and the earth return of the source and a second flexible lead 523 connected between the output of the H.F. source and the first part 524 of an electrical connector mounted by means of insulators 525 on the upper electrode holding plate 509. The second part 526 of the connector is mounted on an electrically connected to the electrode holding plate of the lower assembly 513. A switch 527 for turning off the H.F. current is mounted on the lower bracket 502 and is operable by an adjustable contactor mounted 528 on the upper bracket 501.

45 A further bracket 529 is fixed to the central leg of the frame below the lower bracket slideway. The lower link 530 and upper link 531 of a toggle mechanism are pivotally secured at one end of each respectively to the further bracket 529 and to the lower bracket 502. The other ends of the links and one end of a push rod 532 for the toggle mechanism are pinned together. Movement of the push rod therefore causes the lower bracket to move up and down with respect to its slideway on the frame.

Another bracket 533 is bolted to the frame 3 above the upper bracket 501 slideway. Extending from the end 534 of the bracket remote from the frame is a spring loaded device 535 forming means for moving the electrodes into clamping contact with each other during welding. The device comprises upper 536 and lower 537 parallel members. The upper member 536 is provided with an adjusting screw 538 which passes through the upper member 536 in screw-threaded engagement therewith. On the lower end of the adjusting screw 538 is rotatably mounted a spring-seating member 539. A second spring-seating member 540 is attached to a plunger 541 which extends from the second seating member 540 through the lower member 537. A compression spring 542 is located between the two spring seating members. Rotation of the adjusting screw 538 alters the pre-loading of the spring 542.

The upper end 543 of one link 544 of a second toggle mechanism is pivotally attached to the plunger 541 and the lower end 545 of the second link 546 is pivotally attached to the upper bracket 501. The other ends of the links 544 and 546 are pivotally connected with one end of a push rod 547. Movement of the push rod therefore moves the upper bracket up and down, but, if the upper bracket is prevented from moving down, the push rod is still able to move as the spring 542 compresses. Then if, with the push rod 547 stationary and the spring 542 compressed, the upper bracket 501 does become free to move the spring will urge the upper bracket downwards.

The push rods 547 and 532 (FIG. 9) actuating respectively the upper and lower brackets are connected respectively to cam followers which follow respectively upper and lower welding bracket actuating cams 550 and 551 on the camshaft. The profiles of these cams are such that during rotation of the cams the brackets are moved towards each other until the electrodes 511 and 520 are in contact with the sheet, relatively away from each other slightly, and then relatively towards each other again into clamping engagement with the sheet and to compress the spring 542.

The operation performed in the welding station serves to join the two halves of the sheet to form eight spheres in a double thickness web of the sheet material. The fourth pair of grippers 16 brings the doubled sheet from the cutting and doubling station to the welding station. The welding bracket actuating cams 550 and 551 rotate to actuate the toggle mechanisms to move the brackets 501 and 502 towards each other. This movement continues until the electrodes 511 and 520 just contact the sheet. The passageways 515 leading to the hemispherical surfaces 512 and 519 of the electrodes are then connected to a source of vacuum and the grippers opened to allow the upper and lower halves of the sheet to be drawn respectively into intimate contact with the upper and lower electrodes. Further rotation of the cams and consequent operation of the toggle mechanism moves the brackets relatively away from each other to separate the upper and lower halves of the sheet and ensure that the hemispheres in each half are accurately and securely seated in the electrodes. Since the brackets are mounted in shakefree slideways 504 the two halves of each sphere will be in alignment.

Continued rotation of the cams 550 and 551 relatively moves the brackets together to bring the electrodes and sheet into clamping engagement and to compress the spring 542. At the same time the two parts 524 and 526 of the electrical connector mounted on the upper 506 and lower 516 electrode mounting assemblies come into contact to complete the H.F. circuit. A switch operated by a cam on the camshaft 5 is operated to switch on the H.F. current. Welding takes place about the periphery of the spheres at the junction of the two sheets.

As welding takes place the material softens and flows and the upper bracket 501 is urged towards the lower bracket 502 by the spring 542. When sufficient flow of the material has occurred the contactor 528 on the upper assembly operates the "off" switch 527 on the lower assembly to switch off the H.F. current.

During welding the electrodes 511 and 520 are kept at a substantially constant temperature somewhat above room temperature by passing heating or cooling fluid as required through the temperature control plates 507.

The fifth pair of grippers clamp onto the edges of the sheet, and when welding is complete the vacuum source is shut off, and the brackets moved away from each other to release the sheet and the sheet is transferred by the grippers to the next station.

This method and apparatus for the alignment of the two parts of the spheres is more particularly described in our copending U.S. patent application Ser. No. 601,625 filed Dec. 14, 1966.

Idle Station (600)

The next station is an idle station which forms no part of the invention but is included in the machine as described herein in order that the distances between the stations shall be equal. Since the dimensions of the apparatus required in the welding station and the cropping and trimming station are large it is necessary to include the idle station. Provided in the idle station is a supporting plate 601 for the sheet which is supported on and movable up and down by the end of a lever 602 actuatable by a cam follower 603 and cam 604. In operation when a sheet is brought into the station the plate 601 is raised and the sheet deposited on the supporting plate by the fifth pair of grippers and removed from the supporting plate by the sixth pair of grippers for transference to the next station.

Cropping and Trimming station (700)

When the material arrives in this station it is in the form of a double thickness of sheet with eight spheres formed therein. It is now necessary to remove the spheres from the sheet and to remove flash from the welding line of each sphere.

A right-angle swan-neck bracket 701 (FIG. 11a) is mounted in a dovetail-slideway 702 fixed to the central leg 3 of the frame above the line of motion of the sheet. Above the slideway a cantilever bracket 704 is also fixed to the leg 3. The two links 705 and 706 of a toggle mechanism are pivotally attached by one end of each respectively to the swan-neck bracket 701 and the cantilever bracket 704. The other ends are pinned together and to the end of a push rod 707 linked by a cam follower 755 and upper bracket actuating cam 756. Movement of the push rod 707 causes the bracket 701 to slide vertically in the slideway 702.

On the lower end 708 of the swan-neck upper bracket 701, i.e., that end remote from the slideway 702, is mounted a ball-clamping assembly 709. The assembly comprises a plate 710 secured to the bracket and having eight circular blind bores 711 formed therein, the open ends of the bores facing downwards. The bores 711 have a diameter slightly greater than the diameter of the spheres. Passing through the blind end of each bore is a spring-loaded clamping plunger 712. The ends of the plungers located in the bores have ball contacting pads 713 attached thereto which have ball-engaging surfaces 714 of part-spherical shape.

An open box-like framework 715 (FIG. 11b) is secured by one side to the central leg 3 of the frame in a position below the line of motion of the sheet.

A cropping plate 716 is secured to the upper surface of the framework 715. The plate has eight bores 717 extending therethrough and around each bore is provided a cutting knife 718 which has a circular cutting edge protruding above the upper surface of the plate. The diameter of the cutting edge is slightly larger than the diameter of a ball and the diameter of the bore below the cutting edge is greater again than the diameter of the cutting edge so as to allow a ball to pass through the bore after being cropped from the sheet. Four reception plungers 719 are mounted at the corners of the plate 716 and extend upwardly from the plate. The plungers 719 are lightly spring-loaded so as to be urged in an upward direction.

A pair of parallel tail stock mounting shafts 720 (FIGS. 11b and 12) are suspended in a horizontal plane under upper members 721 of the box frame 715. The shafts extend from a point forward of the cropping plate 716 to the discharge station. A plurality of screw members 722 for each shaft extend through the upper member 721 and into each shaft so as to secure the shaft rigidly with respect to the frame. An adjustable stop 723 provided with a locating and centering shoulder is secured under the rearward end of the upper member of the frame.

A multiple tailstock 724 (FIG. 12) is slidably mounted on the shafts 720 and is slidable by a lever mechanism 757 actuatable by a cam 758 and operating a push rod 725 from a position under the cropping plate 716 and in contact with the adjustable stop 723 to a position in the discharge station.

The tail stock 724 comprises a metal block 724a provided with two longitudinal bores adjacent the upper surface thereof, within which the shafts 720 are located. Grooves 726 are provided in the material of the block between the bores and the said upper surface to allow the screw means 722 to enter the shafts and to allow the tail stock to slide along the shafts.

Eight metal suction pads 727 are rotatably mounted in the lower surface of the block for contacting the upper part-spherical surfaces of the balls as will be seen. Each pad has a part-spherical recess in its lower surface and a passageway 728 is provided to connect the recess to a source of vacuum.

Two vertical columns 715a (FIG. 11b) extend between the upper members 721 and lower members of the box frame. A multiple headstock assembly 730 is located between the columns and is slidable on the columns 715a in a vertical direction. Eight spindles 731 extend from the upper surface of the headstock. Each

spindle has a ball-holding pad 732 formed with a part-spherical recess 733 at its upper end which is complimentarily shaped with respect to, and is adapted to receive the lower part of a ball. The holding pads are of a cross-sectional shape such that they may pass into the bores 717 provided in the cropping plate 716. A passageway 734 extends from the engaging surface of each pad 732 for connection to a source of vacuum.

The spindles are rotatably driven in the same direction by gear trains in the headstock which are driven by a single headstock driving shaft 735 rotatably mounted in the headstock and extending below the headstock. The driving shaft has a keyway 736 therein extending the length of the shaft.

The headstock 730 is linked by link members 760 to a lever and push rod system 761 to a cam 762 on the camshaft, rotation of the cam causing the headstock to move on the columns in a required manner.

Fixedly mounted on the columns at the bottom of the box frame is a drive housing 737. A hollow shaft 738 is rotatably mounted in the drive housing and has a pulley 739 mounted on its lower end which is driven by a driving belt 740 from an electric motor 740a mounted on the box frame.

A key 741 is secured to the inner surface of the hollow shaft 738 and the headstock driving shaft 735 extends through the hollow shaft 738, the key 741 on the hollow shaft engaging in the keyway 736 on the driving shaft. Thus the hollow shaft and driving shaft are relatively axially movable while remaining in driving engagement one with the other.

Eight single point cutting tools 742 (only two of which are shown) are provided for trimming balls mounted on the spindles. Four tools are mounted in each of two tool holders 743 located one at either side of the box framework. Each tool holder 743 is secured to a horizontal slide 744 which slides in a dovetail slideway 745 on the upper surface of a vertical slide 746. Each vertical slide is slidably mounted in a dovetail slideway 747 fixed to side members 748 of the box frame. An extension 749 of the horizontal slide 744 carries at its end a profile follower in the form of a roller 750. Tension springs 751 are connected between the vertical slide and the horizontal slide and urge the tools 742 inwardly towards the spindles 731 and the follower 750 of each tool holder against an associated profile 752 formed on a profile plate 753 secured to the side member 748 of the box frame.

The vertical slide is linked by link members 754 to a lever system 763 to a cutting tool actuating cam 764 on the camshaft 5 which causes vertical movement of the vertical slides 746 and of the horizontal slides 744 and cutting tools 742. This vertical movement causes the profile follower 750 to follow the profile 752 on the profile plate 753 to give a horizontal movement to the cutting tools.

The profile 752 is such that at the lowest vertical travel of the vertical slide 746 the cutting tools 742 are remote from the headstock assembly 730 and at and about the highest vertical travel of the vertical slide the cutting tool 742 follow the arc of a circle of a diameter equal to the required diameter of the balls, the point of each cutting tool being in contact with a ball mounted between the tailstock and the headstock.

The sequence of operations performed in the cropping and trimming station will now be described.

The sixth pair of grippers 16 brings the sheet with eight spheres formed therein (shown in dotted lines in FIGS. 11a, 11b and 12) from the idle station and deposits it on the reception plungers 719. The tailstock 724 is located in the discharge station, that is to the right as seen in FIG. 12, the cutting tools 742 are in their remote horizontal and vertical positions, and the spindles 731 are in their highest vertical position, such that the center of the sphere defining the recess 733 in a ball holding pad 732 is above the center of the sphere of which the circular cutting edge of the cutting knife 718 is a great circle.

Rotation of the upper bracket actuating cam 756 causes actuation of the links 705 and 706 of the toggle mechanism to lower the upper bracket 701 to engage the ball-contacting pads 713 with the upper surfaces of the spheres. Further downward movement of the bracket 701 presses the reception plungers 719 down and the sheet towards the cutting knives 718 until the holding pads 732 on the spindles 731 engage the lower surfaces of the spheres. The passageways 734 in the spindles are connected to a source of vacuum to firmly seat the spheres on the spindles.

Further downward movement of the bracket 701 causes compression of the springs of the clamping plungers 712 and entry of the upper part of the spheres into the blind bores 711 in the mounting plate 710 and the surface of the plate to contact the sheet. During the final part of the downward movement of the upper bracket 701 the headstock assembly 730 is moved downward at the same rate so that the whole sheet approaches the cutting knives 718 and the edges of the bores 711 act as bolsters for the cutting knives 718 as the balls are moved into the bores 717 and cropped from the sheet.

During and after the cropping of the balls from the web the headstock assembly 730 continues the downward movement, the spring-loaded clamping plungers 712 ensuring that the balls pass through the narrow upper end of the bores 717 and remain fast to the holding pads 732 so that the equatorial regions of the spheres are at right angles to the axes of rotation of the spindles.

After the cropping operation the upper bracket 701 is raised to allow the reception plungers 719 to lift the scrap web of material to the center line of the machine where it may be grasped by the seventh pair of grippers for transfer to the discharge station.

The headstock assembly 730 is lowered, the headstock driving shaft 735 sliding in the hollow drive shaft 741, until the balls are below the level of the lowest surface of the tailstock 724. The cam and lever mechanism is actuated to slide the tailstock along the shafts 720 until it contacts the centering and locating shoulder on the adjustable stop 723. The headstock 730 is now raised until the upper surfaces of the balls engage the spherical-shaped recesses in the suction pads 727. The passageways 728 opening to said recesses are connected to a source of vacuum.

The balls are now accurately centered between the tailstock 724 and headstock 730. Also the weld lines are in a substantially horizontal plane.

The electric motor 740a is started to rotate the spindles 731 and thus the balls, by means of the belt 740, hollow shaft 741, driving shaft 735, and gear trains in the headstock 730.

Rotation of the cutting-tool actuating cam 764 now allows each vertical slide 746 to move vertically upwardly and the profile followers 750 to follow the profiles 752 so that the points of the cutting tools 742 contact the balls and traverse a circular arc, the diameter of which is the required diameter of the balls, about the weld line on the ball to trim off any surplus material. This position is shown in FIG. 12.

When trimming is finished the cutting tools 742 are retracted, the vacuum source is disconnected from the passageways 734 in the spindle, and the headstock 730 lowered. The tailstock 724 carrying the finished balls is now moved along the shafts 720 to the discharge station.

The method and apparatus used and provided in this station is further described in our U.S. Pat. No. 3,464,599 granted Sept. 2, 1969.

Discharge Station (800)

In this station a scrap conveyor 801 extending longitudinally of the machine is mounted on the central leg 3 of the frame. The conveyor is driven by a belt 804 from a pulley 805 on the camshaft 5 and through gearbox 806 and shaft 807. The conveyor comprises three parallel belt conveyors 802 the upper runs of which lie in a plane below the line of motion of the sheet.

The tailstock carrying shafts 720 extend into the discharge station from the trimming station. Below the end of the shafts is a collection chute 803 bolted to the central leg of the frame and extending downwardly of the frame.

When the balls have been trimmed as described above the tailstock 724 is moved along the shafts into the discharge station and the vacuum source is disconnected from the passageways 728 in the tailstock allowing the balls to fall into the collection chute 803 whence they go to a barrelling, packaging, marking, or testing facility as may be required.

The scrap web, carried in the seventh pair of grippers 40 16, is brought to the discharge station. The grippers are opened and the web falls onto the scrap conveyor 801 which takes it away for re-grinding and re-use.

Having now described our invention, what we claim is:

1. A method of manufacturing a table tennis ball comprising forming the two halves of a table tennis ball in a single, generally planar sheet of stiff thermoplastic material, dividing the sheet into two separate parts each of which contains one half of said table tennis ball, inverting one part of the sheet relative to the other part of the sheet by means of movable sheet gripping means and locating said two parts adjacent one another in superposed relationship so that the two halves of said table tennis ball are aligned in substantially the relative positions they occupy in the finished table tennis ball, joining said two parts together to form the table tennis ball and removing the table tennis ball from the sheet.

2. A method according to claim 1 in which the sheet is divided into two equal parts by means of a knife.

3. A method according to claim 1 in which one part of the sheet is held by sheet gripping means and inverted relative to the other part of the sheet by rotating said gripping means.

4. A method according to claim 3 in which the inverted one part of the sheet is located on a support member by engagement of at least one ball half with a corresponding sized hole in the support member.

5. A method according to claim 3 in which the other part of the sheet is located in superposed relationship with said inverted one part of the sheet by moving said other part of the sheet in the plane of said sheet relative to said inverted one part of the sheet by means of a pusher member.

6. A method according to claim 5 in which a locating

means is provided up to which said other part of the sheet is pushed by the pusher member to locate said other part of the sheet in superposed relationship with said inverted one part of the sheet.

5 7. A method according to claim 6 in which the locating means is a stop.
